(57) **CLAIM**

The ornamental design for a token, as shown and described.

DESCRIPTION

FIG. 1 is a front view showing my new design for a token; and,

FIG. 2 is a side view thereof, the opposite side being a mirror image thereof.

In the drawings, the broken lines depict portions of the token only and form no part of the claimed design.

1 Claim, 2 Drawing Sheets

FIG. 1

FIG. 2
